United States Patent Office.

H. W. HARKNESS, OF NEW BRITAIN, CONNECTICUT, ASSIGNOR TO HIMSELF AND ANDREW TURNBULL, OF SAME PLACE.

Letters Patent No. 97,396, dated November 30, 1869.

IMPROVEMENT IN LANTERNS.

The Schedule referred to in these Letters Patent and making part of the same.

To all whom it may concern:

Be it known that I, H. W. HARKNESS, of New Britain, county of Hartford, and State of Connecticut, have invented certain new and useful Improvements in Lantern-Guard Supporter, and to enable others skilled in the art to make and use the same, I will proceed to describe its construction and operation, reference being had to the drawings, in which the same letters indicate like parts in each of the figures.

The nature of this invention consists in two whole cast-metal rings, one for the upper end of the lantern, and one for the lower end of the lantern.

From the lower portion of the upper ring, and about one-half of its diameter, is formed a recess or space, to receive a corresponding segmental piece, one end of which is hinged to the said ring-space, and fastened at the opposite end by a clasp-spring or catch.

From the upper edge of the lower ring, and about one-half of its diameter, is formed space, into which is fitted a segmental piece, one end of which is hinged to said ring, and the other end secured to its place by a clasp-spring.

The upper and lower rings, with their hinged segments, are secured in their relative position with each other by perpendicular wires, extending from the lower ring and segment to the upper ring and segment, and their ends secured thereto in the common way.

Thus the upper and lower segments and the connecting or supporting-wires form a door, hung in a perpendicular position, and equal to about one-half the diameter of the body of the lantern, so that by unfastening the clasp-spring, the door will open freely, and a globe removed or inserted quickly and easily, whenever desirable.

Figure 1 is a side elevation.

Figures 2 and 3 are segmental portions of the rings, showing how the segment is fitted to the main ring *b*, and hinged thereto, also how said segments are secured at their opposite end by the clasp-spring *e*.

Sheet 2 shows the rings and segments, as above described, in a more perfect manner.

a a are the upper and the lower portions of a lantern constructed in the common way.

That part of these rings to which the upper and lower portions of the lantern are secured, are made whole, in one piece of cast-metal; and that portion of these rings (formed of segmental pieces *b'*, hinged to the main rings,) to which the guard or fender-wires

are secured, are fitted and hinged by one end into space provided in the rings *b b* or part *b'* thereof, and the opposite end secured in place by a spring-clasp, *e*.

b b are the cast-metal rings, formed of one piece of metal.

b' is a segmental portion of a ring cast on to the ring *b*.

b' is a segmental piece, corresponding with the segment *b'*, one end of which is hinged to the segment *b'*, and the other end secured in its place and position by a spring-clasp, *e*.

c are guard or fender-wires, the upper and the lower ends of which are in or to the two-part ring or segments *b' b'*.

d is a supporting-wire, which is coiled around each of the perpendicular wires *c*, except on the two opposite sides, near the joints. Here the wire *d* hooks or springs over the wire *c*, and aids to hold the whole firmly together. (See sheet 2.)

e are spring-fasteners, secured to the rings or segments *b'*, one end, *f*, of which is coiled, and fits into a depression, *g*, which serves the purpose of holding the two parts *b' b'* firmly together.

h are the hinge-joints, by which the two parts are held firmly in their relative position with each other, to open and close.

The wires *c* may be made more or less curving, to receive a globe of any desirable size, thereby it might be said that the body of the lantern is formed of two perpendicular parts, one part hinged to the other, so that it may be quickly and easily opened and securely closed, whenever desirable.

Thus it will be seen, that if a globe becomes broken, one-half of the guard may be easily and quickly thrown open, the broken one removed, and a new one inserted in its place.

I believe I have thus shown the nature, construction, and advantage of this invention, so as to enable others skilled in the art to make the same therefrom.

What I claim, therefore, and desire to secure by Letters Patent, is—

The metal rings *b b*, cast in one piece, having the part *b'*, in combination with the segmental hinged part *b'*, guard *c*, and supporting-wire *d*, substantially as set forth.

H. W. HARKNESS. [L. S.]
